UNITED STATES PATENT OFFICE

CHRISTIAN BUEHNER, OF MILWAUKEE, WISCONSIN

PADLOCK

Application filed October 15, 1928. Serial No. 312,463.

The invention relates to improvements in padlocks, and has for its object to produce a cheap and secure lock of the type named and provide a novel form of key therefor.

5 The main object of the invention is to provide a lock of the character described, so constructed as to make it practically impossible to pick or open the shackle thereof by any other tool than the key provided for it.

10 Another object of the invention is to provide a lock of the character described which may be easily and cheaply manufactured and assembled, simple in construction, and which will be efficient in carrying out the purposes for which it is designed.

15 With the foregoing and other objects in view, which will appear as the description proceeds, the invention consists in certain novel and improved features of construction, 20 arrangements, and combination of parts, hereinafter more fully described, illustrated in the accompanying drawings, and particularly pointed out in the appended claims, it being understood that various changes in the 25 form, size, and minor details of the structure may be made without departing from the spirit or sacrificing any of the advantages of the invention.

30 For the purpose of facilitating an understanding of my invention, I have illustrated in the accompanying drawings preferred embodiments thereof, from an inspection of which, when considered in connection with the following description, my invention, its mode of construction, assembly, and many of its advantages should be readily understood and appreciated.

35 Referring to the drawings, in which similar characters of reference are employed to indicate corresponding or similar parts throughout the several figures in the drawings:

40 Fig. 1 is a view in section of an embodiment 45 of the invention showing the same in locked position;

Fig. 2 is a view similar to Fig. 1, with the lock in unlocked position;

50 Fig. 3 is a view similar to Fig. 1, looking 55 in the direction of the arrows;

Fig. 4 is a view in perspective of a bolt used in the embodiment of the invention shown in Fig. 1;

Fig. 5 is a view in perspective of the cylinder in which the key passage is formed;

Fig. 6 is a view in side elevation of a key for 55 said lock;

Figs. 7 and 8 are views in perspective of details;

Fig. 9 is a view in section of a modified form 60 embodying the invention;

Fig. 10 is a view in section taken on line 10—10 of Fig. 9;

Figs. 11 and 12 are views in perspective of details used in the modified form of invention; and

Fig. 13 is an elevational view of the end of the key employed in the modified form of the invention.

Referring to the drawings more specifically 70 the reference character 1, designates the body of the padlock which may be substantially rectangular in cross section and of a material suitable for the purpose, such as steel, brass, or the like. The body is preferably 75 made of a single block and has provided therein a transverse bore 2, extending from one side of the body to a point adjacent the other side thereof, said bore 2, being substantially parallel to the top end of the body 80 and lying in the upper portion of the body. A longitudinal bore 3, is provided in said body, said bore 3, extending from the top of said body to a point near the bottom thereof, and lying adjacent one side thereof. A recess 4, adapted for the reception of one end 85 of a shackle or hasp is provided adjacent the other side of said body, said recess being provided in the top edge of said body. A second longitudinal bore 5, extending from the bottom edge of the body to establish communication with the bore 2, is provided in 90 said body, substantially in the center thereof. The bores 2 and 3, terminate in recesses of reduced diameter for a purpose to be herein- 95 after described.

Positioned in the transverse bore 2, for sliding movement thereon, is a suitable member or bolt 6, provided with a recess 7, in one end thereof, in which is adapted to be received 100

a coil spring 8, the other end of which spring is adapted to be received in the reduced end of the bore 2.

The free end of the bore 2, is closed by a screw plug 15, or the like, the head of said plug being countersunk in the side of said body, so as to provide a substantially smooth surface on the outside edge of said body, after the plug 15 has been disposed in place.

10 A shackle or hasp 9 is provided, said shackle having a longer end 10, and a shorter end 11. The longer end 10, is adapted for sliding movement in the bore 3, said longer end 10, being provided with a number of suitable recesses in the wall thereof, one of said recesses 12, being adapted for receiving the end of the bolt 6, when the latter is in locking engagement with said shackle, as clearly shown in Fig. 1, of the drawings. The shorter end 11, of the shackle is adapted to be received in the recess 4, when said shackle is in locked position.

The lowermost edge of the end 10, of the shackle is provided with a recess in which is adapted to be positioned one end of a spiral spring 13, the other end of which spring is received in the lower reduced portion of the bore 3. The side wall of the longer end 10, of the shackle is provided with a recess 14, disposed opposite to the bolt receiving recess 12, the end walls of said recess 14 are adapted to limit the sliding movement of the shackle in the bore 3. As stated, the free end of the bore 2, is closed by a suitable screw plug 15, having the head thereof counter sunk, as shown at 16, in the drawings. The inner end of said screw plug 15, is provided with a projection or lug 17, adapted to be received in the recess 14, for limiting the up and down movement of said shackle. The lower end 10, of the shackle may also be provided with an annular groove, in which is adapted to be fitted a washer 18, of rubber or the like, for assuring proper operation of the shackle in the bore 3.

It will be noted that the spring 13, will normally force the shackle 9 to its upper or unlocked position, as shown in Fig. 2, and when the shackle is in that position, the bolt 6, must of necessity be out of engagement with the recess 12, or in the position shown in Fig. 2. The spring 8, normally forces the bolt to the right as viewed in Figs. 1 and 2.

In order, therefore to permit the spring 13, to force the shackle to its upper or unlocked position, the bolt 6, must be withdrawn from its engagement with the recess 12. To cause a withdrawal of the bolt 6, the following novel and improved means are provided. A 60 hollow cylinder 20, open at its lower end and having a suitably shaped projection or lug 21, integrally formed therewith at the upper face thereof, is provided, said cylinder being adapted to be received in the upper portion 65 of the bore 5. The projection 21, is adapted

to be received in a suitable recess 22, provided in the underside of the bolt 6, whereby, the rotation of the cylinder 20, will cause a sliding movement of the bolt 6. The following means are provided for rotating said cylinder 20. A pair of longitudinal guiding slots 23, are provided in the cylinder 20, said slots extending from the lower open end of said cylinder to a point adjacent the top thereof.

70 A spring 23' is received in said hollow cylinder, and the lower open end of said cylinder is closed by an annular head or member 24, said head 24, having a pair of diametrically opposed lugs 25 adapted to be received in said slots 23, for sliding up and down movement therein. The lower face of the member 24 is provided with a diametric slot or groove 26, for a purpose to be presently described.

80 Adapted to be positioned in the lower portion of the bore 5, is a second hollow cylinder 27, the upper bore of which is adapted to abut against the lower face of the member or head 24. A suitable countersunk screw 28, is provided for securely locking said cylinders 20 and 27 in place in the bore 5. The top of said hollow cylinder 27, is closed by a suitable washer 29, said washer having a diametric slot 30, provided therein, and when in assembled position said slot 30, is adapted to register with the slot or groove 26, provided in the member or head 24, closing the lower end of the cylinder 20. A washer 31, is employed for closing the lower end of said cylinder 27, said washer being provided with a diametric slot 32, said slot being disposed 90 at an angle to the slot 30, in the upper washer 29.

95 A similar washer 33, provided with a diametric slot 34, is provided in the cylinder 27, intermediate the top and bottom thereof, 105 the slot 34, being disposed at an angle to both the slots 30 and 32. It will thus be noted that a substantially tortuous passage is provided between the outside of the cylinder 27, and the groove or slot 26, provided in the 110 head or member 24, closing the lower end of the cylinder 20. It will be readily understood that by the insertion of a proper implement in the groove 26, of the member 24, and rotating the same in a counterclockwise direction, the bolt 6, will be withdrawn and the shackle 9, forced by the spring 13, to the open position.

115 The specially adapted key 40 for insertion in the cylinder 27, for engaging in the groove 120 26, consists of a flat piece of metal, or the like, of a thickness adapted to pass through the slots 30, 32 and 34, and the end thereof being adapted to be received in the groove 26. The 125 said key 40 is twisted to produce the necessary twists therein for adapting it to readily pass through its tortuous mating passage formed in the cylinder 27. The body of the key terminates in a handle 41, and the length of said body of the key is sufficient to permit 130

it to be inserted in the tortuous passage, formed in the cylinder 27, so as to have the free end 42, thereof, received in the groove 26. The key when inserted through the slot

32, will traverse the tortuous passage and the end 42 thereof will engage in the groove 26, and when turned in the proper direction will cause a rotation of the cylinder 20, which will in turn cause a sliding movement of the bolt

6, thereby releasing the shackle 9.

If desired, in the top face of the projection 21, of the cylinder 20, may be provided a suitable ball bearing 43, for engagement with the upper wall of the cut away portion 22, of the bolt 6, for facilitating the rotation of said cylinder 20.

It will be noted that the washers 29, 31, and 33, provided in the cylinder 27, are spaced from each other, the angular relation of the slots in said washers being such as to readily permit the insertion of the key 40, without any impediment. By providing the spaced washers as shown, tampering with a piece of flat metal is prevented, as a tool or implement of sufficient flexibility to be introduced through the tortuous passage formed by the slots 32, 34, and 36, will not retain its form to permit it to rotate the cylinder 20, for withdrawing the bolt 6.

The key 40, is of correct twist and is made of unyielding material and when inserted into its mating passage will transverse the same without impediment until the end 42, thereof, will be received in the groove 26, after which it may be rotated to cause a corresponding rotation of the cylinder 20. A washer 45, of rubber or the like, is provided on the end 10 of the shackle for preventing dust or moisture from getting into the bore 3.

In the modified form shown in Figs. 9 to 12 inclusive, the body 50, of the lock is similar to the body 1, in the first modification. The body 50, is provided with a pair of longitudinal bores 51, and 52, extending completely through the body. Intermediate the bores 51, and 52, is provided a bore 53, similar to the bore 5, the top of said bore 53, being in communication with a transverse bore 54, the ends of which bore 54, communicate with the longitudinal bores 51 and 52. Disposed within the transverse bore 54, is a pair of cooperating bolts 55 and 56, said bolts being provided with collars 57 and 58, in their inner ends, and when in assembled position said collars are adapted to prevent their disengagement from each other. A suitable spiral spring 59, having its ends disposed in suitable recesses 60 is provided in said bolts.

The spring tends to normally extend the said bolts, and by inserting a proper implement between the said collars 57 and 58, when the bolts are in assembled position, and properly rotating said implement, the said collars will be caused to separate, thus moving the ends of said bolts closer together or in-

wardly. The free end of said bore 54, may be closed by a suitable screw plug 60, which may be countersunk in the side of the body of the lock.

Adapted for reception in the longitudinal bores 51 and 52, are the ends of a shackle or hasp 61, the inner side walls of said ends of the shackle being provided with suitable notches 62, which are adapted to engage with the ends of the bolts 55 and 56, for holding the said shackle in locked position, as shown in Fig. 9.

The following means are provided for causing a withdrawal of the bolts in order to permit the removal of the shackle from the body of the lock. Positioned in the upper portion of the bore 53, is a hollow cylinder 63, open at its lower end, and closed at the top, and provided on its closed end with a projection 64, and a pin or stud 65. The projection 64, is adapted to be received between the collars 57 and 58, and when the cylinder 63, is rotated in the proper direction the said projection 64, is adapted for spreading said collars in order to cause an inward movement of the ends of said bolts, thereby withdrawing the same from the engagement with the notches 62, in the shackle 61. Suitable longitudinal guide slots 15, are provided in the sides of said cylinder, and the lower open end of said cylinder may be closed by a suitable member or head 66, which is provided with a diametric groove 67, and through which extends a rod 68, the ends of said rod extending beyond the walls of the head 66, and are adapted to be received and guided in the slots 15, provided in the cylinder 63.

A spiral spring 69, is positioned inside of said hollow cylinder 63, for holding the head 66, against the top of a hollow cylinder 70, which cylinder 70, is constructed in a manner similar to that of cylinder 27, and is provided with a tortuous passage from the outside thereof to the head 66. A suitable screw 71, is provided for securely locking said cylinder 70, in place in the body of the lock.

The operation of the modified form is the same as that of the first form described. The end of the key employed in this modification is bifurcated to straddle the rod 68 when it is inserted into the groove, 67 of the head 66.

The construction of the lock affords means for preventing the picking or opening of the shackle by any other tool than the key provided for it.

It is feasible to slightly change the angular relation between the slots in the washers, thereby changing the twist of the key passage and by making a corresponding change in the twist of the key, a new pattern is formed. It will thus be possible to have no great number of keys of the same pattern made, which will prove an additional advantage secured by this form of lock and key.

It is believed that my invention, its mode of construction, and many of its advantages should be readily understood from the foregoing without further description, and it should also be manifest that while preferred embodiments of the invention have been shown and described for illustrative purposes, the structural details are nevertheless capable of wide variation within the purview of my invention, as defined in the appended claims.

What I claim and desire to secure by Letters Patent of the United States is:

1. A device of the character described, comprising a lock case having twin shackle sockets extending therethrough, a shackle having its legs received in said sockets, each of said shackle legs being provided with a locking notch, a pair of cooperating bolt sections slidably mounted in said lock case adapted for engagement with said shackle legs for holding the same in locked position, a single spring means adapted for holding said bolt sections in extended position, projections provided on said bolt sections adapted for engagement with each other for preventing the disassembly of said bolt sections, an elongated lug disposed between said projections adapted for moving said projections away from each other whereby the ends of said bolt sections will be brought out of engagement with said notches, said lug being carried by a cylinder disposed in said lock case and adapted for rotary movement therein.
2. A padlock comprising a lock case having twin shackle sockets extending therethrough, a shackle having its leg portions received in said sockets, each of said leg portions being provided with a locking notch, sliding, cooperating bolt sections disposed in position for engagement with the notches in the shackle legs for locking the shackle in the lock case, said bolt sections being provided adjacent one end with a segmental projection the inner end of one of said projections being adapted for engagement with the inner end of the other of said projections when the sections are in assembled position, cut out portions provided on each of said bolt sections intermediate the ends thereof for receiving for sliding movement therein the projection of the other of said bolt sections, a single spring means adapted for holding said bolt sections in their extended position, an elongated lug disposed between the inner ends of said projections and adapted, when rotated, to force said projections away from each other and against the action of said spring means, said lug being carried by a cylinder disposed in said lock case, and being adapted for rotary movement therein.
3. A padlock comprising a case having twin shackle sockets extending therethrough, a shackle having its leg portions received in said sockets, each of said leg portions being

provided with a locking notch, a pair of cooperating bolt sections disposed in position for engagement with the notches in the leg portions, said bolt sections being provided with segmental projections adjacent one end thereof, cut out portions provided on each of said bolt sections intermediate the ends thereof for receiving for sliding movement therein the projection of the other of said bolt sections, a single spring means received between said bolt sections and adapted for holding the same in extended position, an elongated lug disposed between the adjacent ends of said projections and adapted, when rotated, for forcing said projections away from each other against the action of said spring means, said lug being carried by a cylinder disposed in said lock case, said cylinder being adapted for rotary movement therein.

In testimony whereof I affix my signature.

CHRISTIAN BUEHNER.
